PLUNGER PUMP

Eric C. Hammarstrom, Peapack, and Charles Russell Ballantyne, Basking Ridge, N.J., assignors to Komline-Sanderson Engineering Corporation, Peapack, N.J., a corporation of New Jersey

Filed Jan. 2, 1959, Ser. No. 54,029

Term of patent 7 years

(Cl. D65—1)

Fig. 1

Fig. 3

Fig. 2

Figure 1 is a perspective view of a plunger pump incorporating the design of our invention.

Figure 2 is a plan view of the pump shown in Figure 1.

Figure 3 is a side elevation of the plunger pump of the invention as viewed from the right hand side in Figure 2.

Figure 4 is a rear elevation of the plunger pump as seen from the right hand in Figure 3.

Figure 5 is a side elevation of the plunger pump as viewed from the left-hand side in Figure 2.

We claim:

The ornamental design for a plunger pump substantially as shown.
